(57) **CLAIM**

The ornamental design for a handheld scanner, as shown and described.

DESCRIPTION

FIG. 1 is a perspective view of the handheld scanner of the present invention;

FIG. 2 is a front elevational view of the handheld scanner of FIG. 1;

FIG. 3 is a rear elevational view of the handheld scanner of FIG. 1;

FIG. 4 is a left side elevational view of the handheld scanner of FIG. 1;

FIG. 5 is a right side elevational view of the handheld scanner of FIG. 1;

FIG. 6 is a top plan view of the handheld scanner of FIG. 1; and,

FIG. 7 is a bottom plan view of the handheld scanner of FIG. 1.

The broken lines shown in the drawings are included for the purpose of illustrating portions of the handheld scanner that form no part of the claimed design.

1 Claim, 6 Drawing Sheets
